(57) **CLAIM**

The ornamental design for a shingle roof panel, as shown and described.

DESCRIPTION

FIG. 1 is a perspective view of a shingle roof panel in accordance with our design;

FIG. 2 is another perspective view of the shingle roof panel in accordance with our design;

FIG. 3 is a top plan view of the shingle roof panel in accordance with our design;

FIG. 4 is a front elevation view of the shingle roof panel in accordance with our design;

FIG. 5 is a left side elevation view of the shingle roof panel in accordance with our design, the opposite side being a mirror image;

FIG. 6 is a right side elevation view of the shingle roof panel in accordance with our design, the opposite side being a mirror image;

FIG. 7 is a back elevation view of the shingle roof panel in accordance with our design; and,

FIG. 8 is a bottom plan view of the shingle roof panel in accordance with our design.

The broken lines showing environmental structure are for illustrative purposes and form no part of the claimed design.
